Primary Examiner — Alison M Ofstun*(74) Attorney, Agent, or Firm* — CANTOR COLBURN LLP**(57) CLAIM**

The ornamental design for an iron for straightening hair, as shown and described.

DESCRIPTION

FIG. 1 is a top-right-front side perspective view of an iron for straightening hair showing my new design;
FIG. 2 is a bottom-left-front side perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof; and,
FIG. 8 is a bottom plan view thereof.

The evenly-spaced broken lines illustrate portions of the iron for straightening hair and form no part of the claimed design. The dash-dot broken lines illustrate a boundary to the claimed design and form no part thereof.
